UNITED STATES PATENT OFFICE.

SANTO ABATE AND JOHN BUONINCONTRI, OF IRVINGTON, NEW JERSEY.

DESIGN FOR A TENSION DEVICE FOR KNITTING.

59,449.

Specification for Design.

Patented Oct. 25, 1921.

Application filed February 10, 1921. Serial No. 444,045. Term of patent 14 years.

To all whom it may concern:

Be it known that we, SANTO ABATE and JOHN BUONINCONTRI, subjects of the King of Italy, residing at Irvington, county of Essex, and State of New Jersey, have invented a new, original, and ornamental Design for Tension Devices for Knitting, of which the following is a specification, reference being had to the accompanying drawing, forming part thereof.

Figure 1 is a perspective view of the new and ornamental tension device for knitting,

showing the device on a finger, part of the hand being shown in dotted outline.

Fig. 2 is a top view of the tension device for knitting, and

Fig. 3 is an end view of the tension device for knitting.

We claim:

The ornamental design for a tension device for knitting, as shown.

SANTO ABATE.
JOHN BUONINCONTRI.
